ABSTRACT OF THE DISCLOSURE

A tertiary recovery process for improving the recovery of oil from a reservoir which has been waterflooded. Said process comprises injecting a material which is somewhat soluble in water and more soluble in the reservoir oil, injecting a second material which is miscible with said first injected material, and injecting a third material which is miscible with said second injected material and which acts as a drive fluid to drive said oil through the reservoir and through a producing well in communication with said reservoir.

This invention relates to a method for increasing the recovery of oil from reservoirs. In one aspect, it relates to a tertiary recovery of hydrocarbons following a water flood by a method of combined flooding media, which is novel and unique in the art, in order that substantially all the oil in a reservoir may be recovered.

In recovery of oil from oil reservoirs, several methods have been proposed for increasing the recovery of the oil in place in the reservoir. Among these proposals has been the injection of water commonly referred to as waterflood, the injection of normally gaseous hydrocarbons, the injection of a 100% pore volume of propane, the injection of propane followed by water, and the injection of a slug of miscible fluid followed by a hydrocarbon gas. The foregoing methods of recovery are commonly referred to as secondary recovery operations in that they are recovery efforts which are applied in order to obtain production subsequent to the economic production obtainable by utilizing naturally occurring energy or conventional pumping means. The use of miscible fluids in secondary recovery operations is known in the art, particularly the injection of low molecular weight normally gaseous hydrocarbons. Methods utilizing such hydrocarbons are extremely successful with regard to the displacement efficiency of the hydrocarbons, particularly the ability to displace essentially all of the hydrocarbons from the formation, but the volumetric efficiency of this flooding media is a disadvantage. The hydrocarbons inherently finger and channel to a great extent and a large portion of the reservoir is bypassed though the volume of injected hydrocarbons may be great. This brings up the further disadvantage of expense per volume and inability to obtain sufficient volumes of the flooding media. These disadvantages are particularly prevalent when miscible flooding is attempted on a reservoir which has been previously waterflooded. This additional flooding following waterflood operations has been termed tertiary flooding. Miscible flooding has been found to be very inefficient for displacing oil after a waterflood. For instance, recovery of oil by miscible flooding following a secondary waterflooding operation typically recovers only about 30% or less of the oil in place.

A typical miscible flooding process is the miscible slug process. In effect this is a liquid-liquid miscibility process which consists of injecting a limited quantity of propane, LPG, or similar solvent into an oil reservoir and pushing this liquid bank toward producing wells with subsequently injected gas. The injected liquid being miscible with reservoir oil results in efficient displacement of the oil. The process in essence consists then of both

2

liquid-liquid and gas-gas miscibility. Miscibility can be explained as that physical condition between two liquids that will permit them to mix in all proportions without an interface being formed by the materials. If the two fluids do not mix in all proportions, they are immiscible.

After waterflooding any reservoir the remaining oil is typically present as immobile oil droplets surrounded by a layer of water; therefore, when miscible flooding is attempted following a waterflood, the propane or LPG solvent is unable to make contact with the oil droplets and thus results in an inefficient recovery of oil from the reservoir.

An object of this invention is to provide an improved process for recovering oil from a reservoir which has been waterflooded.

Another object of this invention is to provide a process by which oil is rapidly recovered from a reservoir which has been waterflooded.

A further object of this invention is to provide an improved miscible flooding process which is suitable for recovering oil from a reservoir which has been waterflooded.

An additional object of this invention is to provide an improved tertiary recovery process which overcomes and avoids the disadvantages of the prior art.

Other objects and advantages of the present invention will become apparent from the following detailed description of the invention.

The foregoing objects are achieved by an improved miscible flooding operation following a waterflooded. This improvement comprises, after waterflooding initially, injecting a material which is somewhat soluble in water and more soluble in the reservoir oil. Said material is followed by a typical miscible solvent, such as propane or LPG, which in turn is followed by a miscible gas to drive the oil through the reservoir. By miscible gas we mean a gas miscible with the miscible fluid immediately ahead of said gas. It is believed that the initially injected material, being slightly soluble in water, penetrates the water layer and, being considerably more soluble in oil, tends to increase the volume occupied by the immobile oil particles thereby making the oil mobile and capable of forming an oil bank ahead of the miscible flood. This process results in an increased recovery of oil from the reservoir in a shorter period of time than is possible without the injection of the initially injected material.

As stated previously, the material which is injected into the reservoir prior to the injection of the miscible fluid is a material which is somewhat soluble in water and more soluble in the reservoir oil. This material can be carbon dioxide, aliphatic alcohols, ketones, aldehydes, acids and esters. These aliphatic materials typically have a solubility in water of about 5 to about 20 grams per 100 milliliters at 20° centigrade. Some specific materials in addition to CO₂ which have been found suitable include: 1-butanol, 2-butanol, 2-pentanol, 2-methyl-2-butanol, propanol, 3-pentanone, butanoic acid, methyl propanoate, and ethyl ethanoate. The quantity of this material which is added to the reservoir is dependent upon the quantity of miscible fluid which is subsequently added and is normally about 1 to 10 percent of the miscible fluid added. Typically the amount of first-injected fluid will be between about .0005 and about .02 hydrocarbon pore volumes.

The miscible fluid which is added to the reservoir following the addition of the first-injected material is a fluid which is miscible with the reservoir oil. The miscible fluid can include ethane, propane, butane and LPG. LPG, as is well known, consists principally of propane with minor proportions of pentane and normally a very small amount of ethane. The quantity of miscible fluid added to the reservoir depends upon the particular reservoir

involved but typically varies between about .05 and about .20 pore volumes.

The miscible gas which is injected into the reservoir following the injection of the miscible fluid is a gas which is miscible with the miscible fluid previously added. This miscible gas can be natural gas, flue gas, nitrogen and other inert gases. The quantity of miscible gas added to the reservoir is dependent upon the reservoir; however, the gas is normally injected in sufficient quantities to drive the reservoir oil through the reservoir and thereafter through a producing well.

The order of injection of materials into the reservoir according to this invention is the material which is somewhat soluble in water and more soluble in reservoir oil, followed by the miscible fluid, which in turn is followed by the miscible gas. In addition, it has been found that the injection of small slugs of water with small slugs of each injected material gives an improved result in some reservoirs. For example, alternate slugs of CO_2 and water are added until the desired amount of CO_2 has been added, butane and water slugs are alternately added until the desired quantity of butane is added, then alternate slugs of natural gas and water are added until the producing wells reach their economic limit.

The method of the present invention is adaptable to application to any hydrocarbon-bearing reservoir but most readily on a field-wide basis wherein the reservoir is traversed by several well bores. The wells may be arranged in a conventional manner such as a five spot or line pattern, or as the individual situation demands, with certain of the wells being used for the injection of the displacement media and others for recovery of the hydrocarbons.

Prior to the application of this method to a reservoir, it is necessary to have certain data on the reservoir which is readily determinable by procedures known in the art: such as, effective floodable pore volume of the formation, average interstitial water saturation, applicable relative permeability characteristics, and amount of displacement hydrocarbon required to maintain miscibility between the reservoir oil and the displacing gas during the life of the flood.

In order to more fully describe the invention, reference is made to the drawings of which:

FIGURE 1 represents a reservoir which has been previously waterflooded.

FIGURE 2 represents a reservoir which has been previously waterflooded and subsequently treated in accordance with this invention.

FIGURE 3 is a graph representing a Berea sandstone core which has been flooded with butane in one instance and waterflooded prior to butane flooding in another instance.

FIGURE 4 is a graph showing a Berea sandstone core which has been waterflooded prior to being treated with butane in one instance and waterflooded followed by butyl alcohol and subsequently flooded with butane in another instance.

FIGURE 5 is a graph showing a Berea sandstone core which has been waterflooded followed by butane in one instance and waterflooded followed by CO_2 followed by propane in another instance.

Referring to FIGURE 1 of the drawings, a subterranean hydrocarbon-bearing formation 15 is traversed by an injection well 1 and a production well 3. Oil droplets 5 surrounded by a layer of water 4 result from previously waterflooded reservoir 15. These oil droplets are shown in an enlarged form for ease of illustration. The oil droplets, which are formed during the waterflood operation, are present in an immovable form and are, therefore, not susceptible to treatment by ordinary miscible flooding to any great degree.

In FIGURE 2 of the drawing, a subterranean hydrocarbon-bearing formation 15 is traversed by an injection well 1 and a producing well 3. A material 9, which is somewhat soluble in water and more soluble in the reser-

voir oil, is injected through injection well 1. A miscible fluid 11 is injected following injection of material 9. A miscible gas 13 is injected following injection of miscible fluid 11. An oil bank 7 is built up by material 9 acting upon oil droplets 5. This bank of oil is subsequently swept through the reservoir and produced as oil through producing well 3. The various lines are shown in FIGURE 2 representing the materials added as interfaces between each material; however, this is done merely for ease of illustration and it must be understood that these are not interfaces in the true sense but are transition zones varying from one end of the zone as a zone rich in hydrocarbon oil through the other extreme zone which is rich in miscible gas. This is the typical situation which is present in miscible flooding. The material represented by numeral 9 in FIGURE 2 can be carbon dioxide or certain aliphatic alcohols, aldehydes, ketones, acids and esters which meet the solubility requirement previously stated.

Referring to FIGURE 3 of the drawing, it can be seen that a Berea sandstone core treated with a butane flood removes essentially all of the included oil with the injection of approximately 2 pore volumes. This figure also shows the treatment of the Berea core with a waterflood followed by butane. As can be seen from the figure, only 40% of the oil is recovered by the waterflood and with the addition of butane at 2 pore volumes only about 72% of the hydrocarbon has been recovered.

Referring to FIGURE 4 of the drawing, a Berea sandstone core is treated in one instance with a waterflood followed by butane with the resulting recovery at any given pore volume of less oil than can be obtained with the addition of butyl alcohol following the waterflood and subsequently a butane flood. For example, at 2.5 hydrocarbon pore volumes injected the waterflood followed by butane gives approximately 77% recovery whereas the waterflood butyl alcohol and butane system at 2.5 pore volumes gives a recovery of approximately 88%.

Referring to FIGURE 5 of the drawing, a Berea sandstone core is treated with waterflood followed by butane and the resulting recovery at 2 pore volumes is approximately 73% whereas the waterflood- CO_2 -propane system gives approximately 88% recovery at 2 pore volumes injected. It should be noted that in this system butane is used in one instance and propane in the CO_2 system. The difference between results at 2 pore volumes would be even greater had CO_2 propane been compared with the propane system, it being known that butane has a tendency to recover a greater percentage of oil than does propane.

In order to more fully disclose and teach the invention, the following examples are included by way of illustration.

Example I

A Berea sandstone core was saturated with oil. Butane was passed through the core and percent oil recovered was compared against hydrocarbon pore volumes injected. At 2.0 pore volumes injected, 100% of the oil was recovered. This core was again saturated with oil. The core was waterflooded to recover about 40% of the oil. Butane was then added and the percent oil recovered was compared to the pore volume injected at 2.0 pore volumes injected, only 72% of the oil was recovered. This experiment shows the effect of a prior waterflood on the results obtained by miscible flooding. The results of this experiment are shown in FIGURE 3.

Example II

A Berea sandstone core was saturated with oil. The core was waterflooded and then butane was injected. Percent oil recovered was compared with pore volume injected. At 2.5 pore volumes injected, 77% of the oil was recovered. This core was then cleaned and saturated again with oil. The core was waterflooded, 0.1 pore volumes of butyl alcohol was injected and butane was added. Percent oil recovered was compared with pore volumes in-

jected. At 2.5 pore volumes injected, 88% of the oil was recovered. This experiment shows the improvement obtained when alcohol is injected prior to miscible flooding. The results are shown in FIGURE 4.

Example III

A Berea sandstone core was saturated with oil. The core was waterflooded and then butane was injected. Percent oil recovered was compared with pore volume injected. At 2.0 pore volumes injected, 73% of the oil was recovered. This core was then cleaned and saturated again with oil. The core was waterflooded, 0.1 pore volumes of CO_2 was injected and propane was added. Percent oil recovered was compared with pore volumes injected. At 2.0 pore volumes injected, 88% of the oil was recovered. This experiment shows the improvement obtained when CO_2 is injected prior to miscible flooding. The results are shown in FIGURE 5.

Example IV

A conventional five-spot well pattern covering 40 acres and located in the Sussex field in Johnson County Wyo., traversed the oil-bearing Lakota sand formation at a depth of approximately 7,200 feet. This reservoir has been previously waterflooded. The formation temperature is 180° F . and pressure is 2200 p.s.i. The method of tertiary recovery of the present invention could most readily be applied to the portion of the reservoir encompassed within the area of the pattern by utilizing the center well as the injection well and the remaining four peripheral wells, at an average distance of about 933 feet from the injector, as recovery wells. The formation sand, having a thickness of 10 feet, has an average porosity of 14 percent, an average permeability of 110 md., and saturations as follows: interstitial water of 54 percent, reservoir oil of 41 percent, and reservoir gas of 5 percent.

Determinations by known methods based on the foregoing data indicate the pore volume of the formation would be 434,000 barrels, containing approximately 178,000 barrels of reservoir oil which is subject to recovery by the present method. The amount of CO_2 , propane and natural gas necessary to effect recovery would be .002, .05, and approximately 3.0 pore volumes respectively; so 62 tons of CO_2 which is 868 barrels at reservoir conditions, 21,700 barrels of propane and approximately 350MM of s.c.f. of natural gas (essentially methane) are injected in that order. The volume of natural gas injected is only approximate since the actual volume injected will depend on when the producing wells reach their economic limit.

The recovery of such a field situation would effect the production of 107,000 barrels of the reservoir oil in place after waterflooding or 60%.

It will be understood that the examples included herein are illustrative only and that the invention is to be taken as limited only by the scope of the appended claims.

What is claimed is:

1. A tertiary recovery process following a waterflood for increasing the recovery of oil from a subterranean reservoir having in communication therewith at least one injection well and one production well comprising:

(a) Injecting into said reservoir through said injection well an amount equal to between about .0005 and about .02 hydrocarbon pore volumes, a slug of a material which is somewhat soluble in water and more soluble in reservoir oil, said material being

selected from the group consisting of carbon dioxide and aliphatic alcohols, aldehydes, ketones, acids and esters, said aliphatic materials having a solubility in water of about 5 to about 20 grams per 100 milliliters at 20° C .;

- (b) Thereafter injecting into said injection well in an amount equal to between about .05 and about .20 hydrocarbon pore volumes, a fluid miscible with said reservoir oil;
- (c) Thereafter injecting into said injection well in quantities sufficient to drive the reservoir oil through said reservoir and thereafter through said producing well, a gas miscible with the miscible fluid of step (b); and
- (d) Alternately injecting small slugs of water with small slugs of each injection of said material of paragraph (a), said miscible fluid of paragraph (b) and said miscible gas of paragraph (c) until the desired quantity of each material has been added.

20 2. A process as recited in claim 1 wherein said first injected material is carbon dioxide, said miscible fluid is selected from the group consisting of LPG, ethane, propane, and butane, and said miscible gas is an inert gas selected from the group consisting of natural gas, flue gas and nitrogen.

25 3. A process as recited in claim 1 wherein said first injected material is 1-butanol, said miscible fluid is butane and said miscible gas is natural gas.

4. A process as recited in claim 1 wherein said first injected material is carbon dioxide, said miscible fluid is propane and said miscible gas is natural gas.

5. A process as recited in claim 1 wherein said first injected material is carbon dioxide, said miscible fluid is butane and said miscible gas is natural gas.

35 6. A process as recited in claim 1 wherein said first injected material is 2-butanol.

7. A process as recited in claim 1 wherein said first injected material is 2-pentanol.

8. A process as recited in claim 1 wherein said first injected material is 2-methyl-2-butanol.

9. A process as recited in claim 1 wherein said first injected material is propanol.

10. A process as recited in claim 1 wherein said first injected material is 3-pentanone.

11. A process as recited in claim 1 wherein said first injected material is butanoic acid.

12. A process as recited in claim 1 wherein said first injected material is methyl propionate.

13. A process as recited in claim 1 wherein said first injected material is ethyl ethanoate.
